US00D983807S

(12) **United States Design Patent** (10) **Patent No.:** **US D983,807 S**
(45) **Date of Patent:** ** *Apr. 18, 2023

(54) **DISPLAY SCREEN WITH A GRAPHICAL USER INTERFACE**

(71) Applicant: **IGT**, Las Vegas, NV (US)

(72) Inventor: **Ernest W. Moody**, Las Vegas, NV (US)

(73) Assignee: **IGT**, Las Vegas, NV (US)

(*) Notice: This patent is subject to a terminal disclaimer.

(**) Term: **15 Years**

(21) Appl. No.: **29/824,303**

(22) Filed: **Jan. 24, 2022**

(57) **CLAIM**

The ornamental design for a display screen with a graphical user interface, as shown and described.

DESCRIPTION

The FIGURE is a front view of a display screen with a graphical user interface showing my new design.

The broken lines showing a display screen and elements of the graphical user interface illustrate portions of the article, and form no part of the claimed design.

1 Claim, 1 Drawing Sheet
